UNITED STATES PATENT OFFICE.

EDWARD J. WIGGINS, OF CHICAGO, ILLINOIS, ASSIGNOR TO DAVID ALBERT HEYMAN,
OF CHICAGO, ILLINOIS.

ELECTRIC VULCANIZER.

1,169,215.

Specification of Letters Patent.

Patented Jan. 25, 1916.

Application filed July 27, 1914, Serial No. 853,327. Renewed June 16, 1915. Serial No. 34,551.

To all whom it may concern:

Be it known that I, EDWARD J. WIGGINS, a citizen of the United States, residing at Chicago, in the county of Cook and State of Illinois, have invented certain new and useful Improvements in Electric Vulcanizers, of which the following is a specification.

My invention relates to electric vulcanizers and has for its general object to provide a simple, cheap and efficient portable electric vulcanizer, such as may be carried in the tool kit of an automobile and used on the current supplied by the automobile battery.

One of the objects of my invention is to provide a construction which will efficiently heat the vulcanizing surface; reduce the exposed area thereof to a minimum so that the vulcanizer may be used out of doors, in the wind, and under otherwise unfavorable conditions; make the same simple, cheap, durable, not liable to get out of order, easy of repair; and capable of facile manipulation.

Figure 1 is a perspective view showing a vulcanizer embodying my invention; Fig. 2 is a longitudinal section through the major portion thereof; Fig. 3 is an enlarged view of the heat unit or cartridge detached; Fig. 4 is an enlarged view of the heat applicator, with a portion thereof in section; Fig. 5 is a transverse section on line 5-5 of Fig. 2.

The heat-applicator element of the vulcanizer, generally indicated at 10, provides a heating head 11, which is preferably made of copper, and preferably takes the form of a rather thin disk, having relatively large planar area and relatively small peripheral area for exposure to the air. An electrical heating element is associated therewith for effective heating of the entire plane surface of the disk and preferably consists of an electric heating coil disposed in an interspace between concentric walls that will, by convection, transmit their heat to the disk. Specifically, the disk 11 has a boss 12 and a central stem 13, that may be integral, and around the boss, spaced apart from the stem 13, is a heating shell 14, the interspace 15 being open for insertion of the heat-coil cartridge. Although a structure providing the separated concentric heat-conducting walls may be constructed in various ways, I prefer that the entire structure be of copper, the shell 14 being a tubing section forced on

the boss 12, so that in effect the structure is substantially unitary.

The heat-coil element in the preferred construction shown is a self-supporting, detachable, cartridge 17, consisting of a mica cylinder 18, arranged to fit nicely on the stem 13 and exteriorly carrying upper and lower connector-rings 19 and 20, to which are secured the ends of the resistance wire 21 that is wound preferably in an open coil, on the mica cylinder. The electrical connections 22-22', are led off from opposite rings 20 and 19, respectively, and the heating unit thus positioned in the space 15 between the two conducting walls 13-14, very effectively heats up the two walls, and consequently the head or vulcanizing plate 11. In practice, I prefer to make the heat unit one that will effectively heat up the disk to say 265° on a low voltage, say 6 or 8 volts, such as may customarily be drawn from a source of supply available on an automobile.

As one effective means of arranging the wiring and also of positioning the heating cartridge 17 fixedly in place, and substantially sealing its open chamber 15, I connect one of the wires, 22, with a screw 23 which is extended through the shell 14 and engages the ring 20, while the other wire 22', I pass through an insulating disk 24 of mica, that overlies the shell 14 and closes the upper end of the heating space 15. An outer casing, properly heat-insulated from the shell 14 is provided, this casing, in the particular construction shown being a tubing-section 27 of metal, bearing on a mica washer 28 and preferably nearly coinciding in size with the disk 11. Vertically the casing preferably extends materially above the upper end of the stem 13, and the comparatively large interspace between the casing and the shell 14 is filled with asbestos wool, or powder, or other heat-insulating material, as at 29. A fiber cap 30 fitting on the upper end of the casing 27 is secured in position by a screw 31 extending into a suitable bore 32 in the stem 13, and the screw head 33 forms a central convex boss for purposes to be described. Thus the shell 27 is clamped in position and so insulated that relatively little heat is imparted thereto, so that the danger of burning the operator is practically obviated and heat wastage is minimized. A handle 35 secured on a stem 36, that makes

threaded engagement with an aperture in the shell 27 serves as a conduit through which the wires are led to the exterior of the device.

5 The applicator 10 coöperates with a frame 40 that affords a heat-insulating pad for opposition to the heating head 11 and also a means of pressure application for forcing the heating head against the pad. Specifically 10 plate 41 is a base plate having formed thereon a central cup or socket 42 carrying a pad 43, of asbestos or other material of relatively low heat conductivity. On the ends of plate 15 41 are solidly mounted two posts 44, one having pivoted thereto at its upper end, as at 45, a bridge bar 46 the free extremity of which is provided with a hook 47 to engage a reduced neck 48 of the other post. A pressure screw 49 extends through a suitable bearing in the bridge-bar in axial alinement with the base pad 43, and its lower end is concaved, as at 50, to coöperate with the boss 33 presented by the head of the screw.

It will be apparent that when the screw 25 49 is run out, the bridge 46 may be swung on its pivoted end disengaging its hook 47 from the neck 48, and leaving an opening between the posts free for insertion of an inner tube of a tire, or other article to be 30 vulcanized. When the bridge is swung back to the position shown in Fig. 1, screw 49 may be run in, its conical end engaging the screw head 33 and centering the applicator 10 with respect to the pad 43, and exerting 35 any desired amount of pressure thereon.

I find in practice that a vulcanizer so constructed may very effectively be used for emergency repairs to automobile tires and the like, its construction causing the vulcanizing head or disk 11 to receive a relatively high degree of heat, and permitting but little heat dissipation even when used in wind or rain. It will be apparent that the device may be readily taken apart for removal of the 40 heating cartridge and the insertion of another, either to vary the resistance to suit the current supply available to a particular user or to permit the replacement in case a heating coil burns out.

50 While I have herein described in some detail a particular embodiment of my invention, it will be apparent to those skilled in the art that changes in the detail of construction might be made without departure 55 from the spirit of my invention and within the scope of the appended claims.

What I claim is:

1. A portable electric vulcanizer, consisting of a frame comprising a base, vertical 60 posts, a bridge movable to span said posts or open the space therebetween, and a pressure screw carried by said bridge; and an applicator providing a heating-head exposed toward the base, an electrical heating 65 unit associated with said head, and a shell

heat-insulated from said heating unit, said shell providing means coöperating with the screw to center the shell upon the base and transmit the screw pressure to the heating-head.

70

2. In a portable electric vulcanizing apparatus, an applicator comprising a heating head, concentric spaced-apart walls forming an annular chamber therebetween, said walls being formed of a material having high heat 75 conducting qualities, and the ends thereof adjacent the heating head being intimately connected therewith, an electric heating coil positioned in the said annular chamber, and a casing surrounding and heat-insulated 80 from said walls.

80

3. In a portable electric vulcanizing apparatus, an applicator comprising a heating head, concentric spaced-apart walls forming an annular chamber therebetween, said walls being formed of a material having high heat conducting qualities and the ends thereof adjacent the heating head being 85 intimately associated therewith, a removable annular cartridge comprising an insulating cylinder and an electric heating coil wound thereon, positioned in said annular chamber and a casing surrounding and heat-insulated from said walls and having a handle.

90

4. A portable element, comprising, in combination, a vulcanizer head; separated concentric walls extending at right angles to said head; a removable annular cartridge in the space between said walls, comprising an insulating cylinder, a coil of resistance wire wound thereon, and conducting rings mounted adjacent the ends of said insulating cylinder and to which the ends of the heat coil are connected; and a casing 100 surrounding and heat-insulated from said walls and having a handle.

100

5. In a portable electric vulcanizer, the combination of a frame comprising a base and a bridge connected thereto; an electrically heated applicator providing a heating head exposed toward the base, and means carried by said bridge and coöperating with the applicator for pressing said heating head toward the base.

105

6. In a portable vulcanizer, the combination of a frame comprising a base and a bridge connected thereto; an electrically heated applicator providing a heating head exposed toward the base, a centrally located projection on the end of said applicator opposite to the heating head end, and means carried by said bridge and coöperating with said projection to center the applicator and press the same toward the base.

110

7. A portable element comprising, in combination, a vulcanizer head, separated concentric walls extending from said head, an insulating cylinder between said walls, a coil of resistance wire wound thereon, con- 120

120

130

tacting rings mounted adjacent the ends of said insulating cylinder and to which the ends of the resistance coil are connected, and a casing surrounding and heat insulated 5 from said walls.

8. In a device of the character described, the combination of a casing, an insulating cap on one end of the casing, a heating disk at the other end of the casing having a stem 10 extending into the interior of the casing, a screw connecting said cap and stem, a shell in heat-conducting contact with the disk interposed between the casing and the stem spaced apart from both thereof, a closure 15 for the top of the space between the shell and stem arranged below the level of the cap for the casing, a heating coil in the open space between said stem and shell, and a body of heat-insulating material filling 20 the space between the casing and cap and the shell and closure.

9. In a portable electric vulcanizer apparatus, the combination with a frame, comprising a base, separated posts extending

upward from said base, a heat-insulating 25 pad on the base, a bridge spanning the posts and movable to open or to bridge the space between the posts, and a pressure screw carried by said bridge and having a recessed end; of an applicator, comprising a heating 30 disk, a stem extending therefrom, a casing surrounding and spaced apart from said stem, a heating coil surrounding the stem, a cap for the casing and a screw securing 35 said cap to the stem and providing a central boss coacting with the depression of the pressure screw of the frame to center the applicator on the insulating pad and to communicate pressure from the screw to the heating disk.

In testimony whereof I hereunto set my hand in the presence of two subscribing witnesses.

EDWARD J. WIGGINS.
